UNITED STATES PATENT OFFICE.

BURNETT M. HENNEY, OF SPRINGFIELD, ILLINOIS.

INCUSTRATION PREVENTIVE.

SPECIFICATION forming part of Letters Patent No. 397,547, dated February 12, 1889.

Application filed May 24, 1888. Serial No. 274,948. (No specimens.)

To all whom it may concern:

Be it known that I, BURNETT M. HENNEY, a citizen of the United States, residing at Springfield, in the county of Sangamon and State of Illinois, have invented a new and useful Improvement in Steam-Boiler Purgers or Cleaners—a process by means of which the scale or incrustation of the boiler may be dissolved and drawn out and the heating capacity of the boiler be kept at a maximum; and I hereby declare the same to be a description of my invention or process which will enable others skilled in the management and care of steam-boilers to make and use the same.

Heretofore steam-boilers have been cleaned or purged by various compounds or processes more or less imperfect or defective; but this process or compound does its work in a thoroughly complete and satisfactory manner, being both a cleaner and a preservative of the boiler.

The object of my invention is to keep the boiler and all steam and water pipes connected therewith perfectly free and clean of all solid sediment or incrustations that may form on the inner surface from the boiling of the water; to prevent the water from foaming or swelling, and thus economize both fuel and water; to dissolve and remove the scale from old boilers, where it has formed and collected from long and constant usage while the boiler is in use, and to preserve the metal of which the boiler is made. I attain these objects by the use of my invention at regular or irregular intervals of not more than once each day the boiler or boilers may be in use. It is a liquid compound, made of common kerosene-oil and walnut-bark juice or extract mixed in equal quantities.

The composition may be used at certain

times or intervals, using about one pint at a time for a boiler of fifty-horse power. A regular application of this quantity will keep any boiler clean and free of all scale or incrustations if used once in twenty-four hours. 45 By constantly using it once every day the thick hard scale of an old boiler made foul by long and constant use will become dissolved into a fine floating sediment which can be readily drawn off by means of the blow- 50 pipe.

The liquid is to be put into the water-tank from which the boiler is supplied, or it may be pumped directly into the boiler separately from the water, there being no danger from 55 explosion in its application. The walnut-bark alone dissolves the softer part of the scale, while the kerosene penetrates to every part of the boiler-surface and of the water and steam pipes connected therewith, and 60 loosens and dissolves all into a fine floating sediment, as previously stated, leaving all clean and free from scale, as if new iron.

A striking advantage my invention has over all other processes now in use is its simplicity 65 and cheapness, and the thoroughness with which it loosens and removes the scale from every part of the boiler and of the pipes connected therewith; also in its preserving and benefitting the boiler-iron.

Having thus described my invention, what I desire to claim and secure by Letters Patent is—

A steam-boiler-purger compound composed of kerosene and walnut-bark juice, or extract, 75 as described and set forth.

BURNETT M. HENNEY.
